Primary Examiner — Marie D. Fast Horse*(74) Attorney, Agent, or Firm* — Thomas J. Nikolai; DeWitt LLP(57) **CLAIM**

The ornamental design for a ceiling fan light kit, as shown and described.

DESCRIPTION

FIG. 1 is a top perspective view of a ceiling fan light kit showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof; and,

FIG. 9 is another perspective view of the ceiling fan light kit in accordance with my design, shown in its environment.

The additional broken lines in FIG. 9 showing the ceiling fan blades, down-rod, and canopy depict environmental structure only and form no part of the claim; while all other broken lines in the drawings depict portions of the ceiling fan light kit that form no part of the claimed design.
